United States Patent Office.

HENRY J. HANCOCK, OF NEW YORK, N. Y.

Design No. 3,158, dated August 11, 1868.

DESIGN FOR SEWING-MACHINE FRAMES.

The Schedule referred to in these Letters Patent and making part of the same.

TO ALL WHOM IT MAY CONCERN:

Be it known that I, HENRY J. HANCOCK, of the city, county, and State of New York, have originated a new and ornamental Design for Sewing-Machine Frames, of which the following is a full, clear, and exact description, reference being had to the accompanying drawing, forming part of this specification, and in which—

Figure 1 represents a side view of a sewing-machine frame made after my new and ornamental pattern or design, and

Figure 2 a transverse section of the same through the line *xx* in fig. 1.

Similar letters of reference indicate corresponding parts.

In the accompanying drawing—

A represents the main body or portion of the frame, which is generally of circular form, and of an eccentric character, being struck from different centres, *a* and *b*, and broken away or interrupted, as at *c*.

Said main body or portion is made up of rims, *d e*, with a plate-like filling to them, near either end or front extremity, perforated by openings *f*, of diamond-shape, and of successively increasing size in a backward direction, while the remainder of the interior is for the most part made up of bars forming diamond or lozenge-shaped openings, *g*, and apertures, *h*, of a triangular character.

The rims *d* and *e* are shaped in their lower portions with points *z z z z*, between which is a circular formation, *k*, mounted by an ornamental cap-piece or projection, *i*, and formed below with an ornamental base-projection, *k*, said circular formation *k*, which may be decorated with a looking-glass, *S*, also having projecting from it, on the one side, plate-like formations or tables, *l m*, the upper one, *l*, of which is of tapering thickness, while the lower one, *m*, is of uniform thickness, with its edge or edges of the same contour as the ends of the base-projection *k*.

The lower front portion of the frame terminates in overhanging flanges or noses, *n n*, immediately below which, in front, is a block-like projection, *o*. There is also another block-like projection, *p*, in rear of the body of the frame, and at a little distance above, also in rear, a further block-like projection, *r*, carrying a column, *a'*, of the configuration represented in the drawing.

The upper front portion of the frame has a rounded termination, as at *s*, with a front and lateral plate-like formation, *u*, having a "snug"-like projection, *v*, and mounted by a cross-cylinder, *w*.

On the upper part of the frame, between the column *a'* and cylinder *w*, is mounted an ornamental projection, *y*, of the configuration represented in the drawing.

What I claim, and desire to secure by Letters Patent, is—

The design for sewing-machine frames herein described, and shown in the accompanying drawing.
